COIN-CONTROLLED APPARATUS AND
CHANGE MAKER

Marvin G. Nelsen, Skokie, Ill., assignor to Guardian Electric Manufacturing Co., Chicago, Ill., a corporation of Illinois

Application April 15, 1947, Serial No. 741,631

13 Claims. (Cl. 194—10)

1

This invention relates to coin controlled apparatus and change maker and is particularly adapted for use with vending machines for vending articles such as frozen foods, cigarettes, drinks, tickets, et cetera.

It is an object of the invention to provide coin controlled apparatus and a change maker which is very fast and accurate in its operation.

It is another object of the invention to provide an extremely simple mechanism for coin controlled and change making apparatus which to a large extent utilizes substantially standard relays and solenoids.

It is a further object of the invention to provide improved change making apparatus and electrical circuit therefor.

It is also an object of the invention to provide an improved and simple electrical circuit for coin controlled and change making apparatus for vending machines.

It is still another object of the invention to provide coin change making apparatus which pays out odd pennies as well as coins of larger denominations.

It is a further object of the invention to provide coin controlled and change making apparatus which will vend articles over a wide range of price and deliver the correct change and which is also readily adjustable to change the price of the article to be vended.

It is still a further object of the invention to provide coin control and change making apparatus which is extremely fast in operation and is, on the other hand, reduced in its speed of operation sufficiently to insure that full credit is given for each coin utilized and correct change is delivered.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is a top plan view of the apparatus for vending articles and making change embodying the invention;

Figure 2 is a view, partially in section, of the rear of the contact plate and movable contactor, taken on line 2—2 of Figure 1;

Figure 3 is a partial view of the mechanism illustrating various coin operated switches, taken on line 3—3 of Figure 1;

Figure 4 is a partial sectional view of the apparatus, taken on line 4—4 of Figure 1, illus-

2

trating a change pay-out solenoid and a snap switch associated therewith;

Figure 5 is a partial sectional view, taken on line 5—5 of Figure 1 showing one of the interlock relays;

Figure 6 is a partial sectional view, taken on line 6—6 of Figure 1 showing one of the impulse relays;

Figure 7 is a partial sectional view, taken on line 7—7 of Figure 1 showing another impulse relay; and

Figure 8 is a diagrammatic view of the apparatus including a schematic wiring diagram.

Referring specifically to the drawing for a detailed description of the apparatus and circuit, and particularly to Figures 1 and 8, numeral 11 designates a base plate on which are mounted a coin chute coin rejecting apparatus and switches generally indicated at 12, and a number of relays, solenoids and contact elements. Specifically, the base plate supports an add stepper relay 13, a subtract stepper relay 14, a contact carrying plate 15, a pair of interlock relays 16 and 17, a pair of impulse relays 18 and 19, a slow release relay 21, an intermediate relay 22, an interlock switch 23, a vending solenoid 24, a change solenoid 25 for releasing nickels or coins of larger denominations, a change solenoid 26 for releasing pennies and, if desired, a selenium rectifier 27.

The add relay 13 comprises a coil 28 and an armature 29 pivoted at 31. The armature 29 is provided with an extension 32 which is adapted to engage with teeth 33 of a ratchet wheel 34, which is secured to a shaft 35 journaled in the front of an upright rectangular frame generally indicated at 36. A spring 37 secured to the armature 29 and to a stud 38 tends to bias the armature upwardly and out of engagement with the ratchet wheel 34. A detent 30 is provided for ratchet wheel 34. The add relay 13 is adapted to rotate the ratchet wheel 34 in one direction.

The subtract relay 14 comprises a coil 39 and an armature 41 pivoted at 42. The armature 41 is provided with an extension 43 which is adapted to engage the teeth 33 of ratchet wheel 34, to rotate the wheel in the opposite direction from the add relay 13. A spring 44 secured to the armature 41 and to the stud 38 tends to bias armature 41 upwardly and out of engagement with teeth 33. A relay operated switch generally indicated at 45 above the subtract coil comprises a pair of fixed contacts 46 and 47 and movable contacts 48 and 50b, which

are mounted on an arm snapped between the fixed contacts 46 and 47 by operating member 49 which is moved by armature 41 and a hairpin spring 51, which causes the snap action. Terminals 50 and 50a are provided for one of the fixed contacts 46 and for movable contact 48.

The contactor plate 15 is supported from the front of the rectangular frame 36 from studs 52 and has a large number of contacts 53 arranged in a circle thereon and extending completely through plate 15. Also mounted on the plate 15 is a spring contact 54 extending from the front of the plate to a position in back thereof and continuously engaging a contact disc 55 which is mounted on shaft 35 and rotates therewith. This is best shown in Figures 1, 2 and 8. The disc 55 is provided with a projecting arm 56 having a contact button 57 thereon, which engages with one of the contacts 53 depending on the position of ratchet wheel 34 and disc 55.

Referring now to the interlock relays 16 and 17, these are identical in construction, except for the number of contacts on the switches, and are best shown in Figures 1, 5 and 8, only one side view being illustrated since the relays are the same. However, for the sake of clarity of the wiring diagram, Figure 8, the parts of each relay will be given separate numbers and relay 16 may be referred to as "Interlock Relay #2" and relay 17 as "Interlock Relay #1." Relay 16 comprises a pair of coils 58 and 59 mounted on a suitable frame supported on base plate 11. Coil 58 is provided with a pivoted armature 61 normally urged away from the coil by a spring 62. Armature 61 is provided with an upwardly extending switch operating member 63 and with a latch element 64. An armature 65 is associated with coil 59 and is normally held away from coil 59 by a spring 66. The bottom edge of the armature 65 cooperates with latch element 64 to hold armature 61 in its lower position, for a purpose hereinafter explained. Stops 67 and 68 for respective armatures 61 and 65 limit movement thereof away from coils 58 and 59.

The switch operating member 63 operates a switch generally indicated at 69, which comprises two movable switch blades 71 and 72 each having a contact 73 and 74 thereon, respectively. Two relatively fixed spring switch blades 75 and 76 are associated with the respective movable switch blades 71 and 72 and have respective contacts 77 and 78 thereon. Terminals 80 and 81 are associated with the respective movable blades 71 and 72 and terminals 82 and 83 are associated with the two fixed blades.

The interlock relay 17 comprises a pair of coils 84 and 85 mounted on a suitable frame 87 supported on base plate 11. Coil 84 is provided with a pivoted armature 88 normally urged away from the coil by a spring 89. Armature 88 is provided with an upwardly extending switch operating member 91 and with a latch element 92. An armature 93 is associated with coil 85 and is normally held away therefrom by a spring 94. The bottom edge of armature 93 cooperates with the latch element 92 to hold armature 88 in its lower position for a purpose hereinafter described. Stops 95 and 96 for respective armatures 88 and 93 limit movement thereof away from coils 84 and 85.

The switch operating member 91 operates a switch generally indicated at 97 which comprises

three movable switch blades 98, 99 and 101 each having a contact 102, 103 and 104 thereon, respectively. Three relatively fixed spring switch blades 105, 106 and 107 are associated with the respective movable switch blades and have respective contacts 108, 109 and 111 thereon. Terminals 112, 113 and 114 are associated with the respective movable switch blades 98, 99 and 101 and terminals 115, 116 and 117 are associated with the respective fixed switch blades, 105, 106 and 107.

Referring specifically to Figures 6 and 7 for a detailed description of the relays 18 and 19, which may be termed a dime and a quarter relay, respectively, numeral 121 designates similar upright spaced plates which are mounted on the base plate 11. The plates 121 have square cutouts 122 therein bent over to form horizontal supporting flanges 123. L-shaped brackets 124 are supported by angles 125 secured to the plates 121, which L-shaped brackets 124 support respective electromagnets or coils 126 and 127, respectively, for the relays 18 and 19, as well as copper time delay slugs 128 and 129 below each of the coils.

The angles 125 are provided with overhanging portions 131 having apertures therein (not shown) which provide knife edges or pivot points for pivoted armatures 132 and 133 associated with the coils 126 and 127, respectively. The armatures 132 and 133 are provided with grooved extensions 134 and 135, respectively extending through the aforesaid apertures to retain the armatures in position on their pivot points. Brackets 136 having downwardly turned flanges 137 are secured to angles 125 and limit movement of the armatures 132 and 133. Angles 125 are also provided with lower horizontal extensions 138 and tension springs 139 are connected between the extensions 134 and 135 of armatures 132 and 133 and extensions 138 of angles 125.

Laminations 141 of insulating material are secured to the tops of the brackets 136 and retain fixed contact arms 142 and 143 and a movable contact arm 144 above coil 126 and fixed contact arms 145 and 146, and movable contact arm 147 above coil 127. Extensions 148 from brackets 136 extend horizontally above the main portion of armatures 132 and 133 and provide upper limit stops therefor.

The movable contact arms 144 and 147 extend through slits 149 in insulating pieces 151 attached to the outer ends of the main parts of armatures 132 and 133, as best shown in Figure 1. The movable contact arms 144 and 147 are formed of spring steel and have flexible fingers 152 and 153 cut therefrom carrying contacts 154, 155, and 156, 157 on opposite sides of the respective flexible fingers 152, 153. Hairpin springs 158 are anchored at one end to an intermediate portion of the movable contact arms 144 and 147, and at the other end to the flexible fingers 152 and 153, respectively. The fixed contact arms 142 and 143 of relay 18 are provided with contacts 159 and 161, respectively, and fixed contact arms 145 and 146 of relay 19 are provided with contacts 162 and 163, respectively. The hairpin springs 158 provide for snap-acting movement of the movable fingers 152 and 153 after the corresponding armatures 132 and 133 are moved downwardly by energization of coils 126 and 127 and after the armatures are moved upwardly by the tension springs 139 upon de-energization of the coils 126 and 127.

Extensions 164 and 165 secured to the main

portion of armatures 132 and 133 extend through lower slits (not shown) in the insulating plates 151 and leaf spring members 166 are secured to the extensions and bias wire pawls 167 and 168 toward ratchet wheels 169 and 171 of relays 18 and 19, respectively. The ratchet wheels 169 and 171 are journaled on shafts 172 and 173, respectively, supported from the upright supporting plates 121. The outer ends of plates 121 are cut and provided with oblique flanges 174. Leaf springs 175 are secured to the plates 121 adjacent the oblique flanges 174 and retain detent balls 176 in engagement with the ratchet wheels 169 and 171 through apertures (not shown) in oblique flanges 174 to add slight resistance to rotation of the ratchet wheels.

Laminations 171 are secured to the underside of flanges 123 and substantially fixed spring contact arms 178 and 179, carrying respective contacts 181 and 182 for respective relays 18 and 19 and movable spring contact arms 183 and 184 associated with the fixed contact arms 178 and 179 and carrying contacts 185 and 186, respectively. Up to this point, it will be noted that the relays 18 and 19, that is, the dime and quarter impulse relays, are identical.

A wheel, 187, preferably formed of insulating material is mounted on shaft 172 and rotates therewith when ratchet wheel 169 is rotated. Eight equally spaced notches 188 are provided in the periphery of wheel 187. Movable contact arm 183 is provided with an angular extension 189 shaped to fit into the notches 188.

A wheel 191, also preferably formed of insulating material, is mounted on shaft 173 of relay 19 and rotates when ratchet wheel 171 is rotated. Four equally spaced notches 192 are provided in the periphery of wheel 191. Movable contact arm 184 is provided with an annular extension 193 shaped to fit into the notches 192.

Terminals 194, 195 and 196 are provided on the upper fixed switch arm 142, the movable switch arm 144 and the lower fixed switch arm 143, respectively, of relay 18 and terminals 197 and 198 are provided for the coil 126 of relay 18. Likewise, terminals 199, 201 and 202 are associated with the upper fixed contact arm 145, the movable contact arm 147 and the lower fixed contact arm 146, respectively, of relay 19. Terminals 203 and 204 are provided for coil 127 of relay 19.

The slow release relay 21 comprises an upright angle member 203 supported from the base plate 11, which supports a coil 205 provided with a group of time delay copper slugs 206 therebelow. An armature 207 is associated with the coil 205 and is normally biased away from the coil by a tension spring 208, a stop 207 limiting the upward movement of the armature. A switch, generally indicated at 203, is also supported on the angle 204 and comprises a relatively fixed spring contact arm 209 having a contact 211 thereon and a movable spring contact arm 212 having a contact 213 thereon. A plate of insulating material 214 is secured to the armature 207 and the end of the movable contact arm 212 extends therethrough and is moved up and down upon energization and deenergization of the coil 205. The coil 205 is provided with two terminals 215 and 216 thereon and the switch 203 is provided with two terminals 217 and 218 on the fixed and movable contact arms 209 and 212, respectively.

The intermediate relay 22 comprises an angle member 219 supported on the base plate 11, which angle member in turn supports a coil 221.

A pivoted armature 222 is associated with the coil 221 and a tension spring 223 normally retains the armature 222 away from the coil 221. A switch generally indicated at 224 is mounted above the coil 221 and includes a movable contact arm 225, having a contact 226 thereon and a relatively fixed spring contact arm 227 having a contact 228 thereon. A plate of insulating material 229 is connected to the armature and the end of the movable contact arm 225 extends therethrough and is moved up and down upon energization and deenergization of the coil 221. A stop 231 limits the upward movement of the armature 222. The coil 221 is provided with two terminals 232 and 233 and the switch 224 is provided with a terminal 234 for movable contact arm 225 and a terminal 235 for fixed contact arm 227.

The interlock switch 23 comprises a movable contact arm 236 having a contact 237 thereon, a fixed contact arm 238 having a contact 239 thereon, and a stop arm 241. The movable contact arm 236 is normally biased to a position where contacts 237 and 239 are held closed by a spring 242. The movable contact arm 236 is adapted to be moved by operation of the nickel change pay-out solenoid 25 through the medium of an arm 243 in a manner hereinafter described. A terminal 244 is provided on the movable switch arm 236 and a terminal 245 is provided on the fixed switch arm 238.

The vending or package discharge solenoid 24 comprises a coil 246 and a movable armature 247. The nickel solenoid 25 comprises a coil 246b and an armature 247b. The penny solenoid 26 comprises a coil 246a and a movable armature 247a. The armature 247b of the nickel solenoid 25 extends through the coil 246b a sufficient distance to move the member 243 on the interlock switch 23 to open contacts 237-239. The package or vending solenoid 24 is disposed adjacent a slide 248 which is moved by the armature 247 to drop a package of material to be vended through a package chute (not shown). The nickel pay-out solenoid 25, when energized, operates the armature 247 to move a slide 259, thereby dropping a nickel 251 through a suitable change chute (not shown). The armature 247a of the penny pay-out solenoid 26 operates a slide 252 to drop one or more pennies 253 through a change pay-out chute (not shown).

The coin switch and rejection mechanism 12 is of standard design and in the present case includes three micro-switches 254, 255 and 256, which are respectively operated by nickels, dimes and quarters, respectively, dropping through the proper chutes of the coin mechanism 12. The nickel chute is indicated at 257, the dime chute at 258, and the quarter chute at 259. The nickel switch 254 is provided with terminals 261 and 262, the dime switch 255 with terminals 263 and 264, and the quarter switch 256 with terminals 265 and 266. These switches 254, 255 and 256 each contain contacts therein (not shown) which are closed when a coin passes through the respective chutes and operates coin actuated arms 267, 268 and 269 on the respective nickel, dime and quarter switches.

The coin chutes rejecting mechanism and coin switches are of conventional design and form no part of the present invention per se. The selenium rectifier 27 is also standard equipment and may be used where it is desired to operate the various relays and solenoids on direct current from an alternating current source of supply. Further description of the coin chute, rejecting

mechanism, coin switches, and rectifier is therefore deemed unnecessary.

Operation

As best shown in Figures 2 and 8, the mechanism and wiring is arranged to dispense or vend an article priced between 30¢ and 35¢. For this reason, connections are made to the sixth contact numbered 53a and the seventh contact numbered 53b (counting from the initial contact 53c of the contact plate 15 carrying the contacts 53). There is also a connection to the initial contact 53c.

While the example shown is arranged to dispense or vend an article of 35¢ value, or between 30¢ and 35¢ value, it will be obvious as the description proceeds that different priced articles may be vended and change made with the mechanism and circuit shown by merely changing the connections 53a and 53b. It will also be apparent that the penny pay-out solenoid may be utilized if the article to be vended is an odd number of cents, whereas the penny pay-out solenoid is unnecessary if the article to be vended is an even multiple of nickels, dimes or quarters. It will also be obvious as the description proceeds that instead of the machine being adapted to operate on nickels, dimes and quarters, it may, for example, accept dimes, quarters, and half dollars and, in each case, pay out the correct change, depending upon the price of the article to be vended or dispensed. The only limitation on the price of the article is in the denomination of coins which may be used and the number of contacts 53 which are placed on the contact plate 15. It is, therefore, obvious that the mechanism is practically unlimited in its ability to vend articles or merchandise of different prices and to deliver the correct change.

When a nickel is inserted in the coin chute 12, nickel contacts 261, 262 are closed and a circuit is established from D. C. line L1, through conductors 270, 271, contacts 261, 262, conductor 272, through slow release relay coil 205 and back to D. C. line L2 through conductor 273. The slow release coil 205 is, therefore, energized and opens slow release contacts 211 and 213 to prevent circuits being established through the interlock relay contacts.

An additional circuit is also established from D. C. line L1, through conductors 270, 271, contacts 261, 262, conductor 272, conductor 234, through add relay coil 28 and conductors 275, 277 back to D. C. line L2. The add coil is thus energized one time and contact arm 56 is moved clockwise, as viewed in Figure 8, a sufficient distance to have the contact arm engage the next adjacent contact 53. Obviously, there can be no circuit then established through conductor 278 leading from the initial contact 53c to terminal 117 of fixed contact arm 107 of the interlock relay 17 (interlock relay No. 1) or to the subtract coil 39, until the contact arm 56 again returns to engage initial contact 53c.

Assuming now that a dime is initially inserted in the coin chute 12, a circuit is established from line L1, through conductors 270, 271, and 278a, through contacts 263, 264, conductor 279 to coil 126 on the 10¢ impulse relay 18, and back to line L2 through conductors 283 and 273. The armature 132 of the relay 18 is therefore drawn downwardly and wheel 187 is turned so that switch contacts 181, 185 are closed. Furthermore, normally closed contacts 155, 161 are opened and contacts 154, 159 are closed. Opening of contacts 75

155, 161 breaks a circuit through line L1, through conductors 270, 282, through contacts 181, 185, conductor 283 to terminal 195 on movable switch arm 152, contacts 155, 161, through conductor 284a, through coil 126, and conductors 288, 273 back to line L2. The coil 126 is, therefore, de-energized. However, a circuit has been established when contacts 154, 159 close from line L1, through conductors 270, 282 contacts 181, 185, conductor 283, contacts 154, 159, conductor 285 through slow release coil 205 and back to line L2 through conductor 273. The slow release coil 205 is, therefore, energized and contacts 211, 213 are held open to prevent energization of the interlock relays and the subtract coil 39. Because of the copper slugs 206 on the slow release coil, the armature 207 will be held in the down position even though pulsating rather than continuous current is flowing through the coil 205. Another circuit is also established at this time to energize the add coil 28. This circuit starts at line L1 and follows the same course just described up to the slow release coil 205. The additional circuit is established from conductor 285, through conductor 284, add coil 28, and conductors 275, 277 to line L2. One credit is, therefore, established and contact arm 56 is moved clockwise away from initial contact 53c to the next contact 53.

The opening of contacts 155, 161 having broken 30 the circuit to the 10¢ relay coil 126, and thereby deenergized it, causes its armatures to release to again close contacts 155, 161 and open contacts 156, 159, thus deenergizing the add coil 28. However, the slow release relay 21 does not immediately release armature 207, as explained above. Closing of contacts 155, 161 again energizes coil 126 of the 10¢ relay through a circuit starting at line L1, through conductors 270, 282, contacts 181, 185, conductor 283, contacts 155, 161, conductors 284a, 288 and 273 back to line L2. Energization of coil 126 is again effected, therefore, and contacts 155, 161 open and contacts 154, 159 close, thus maintaining contacts 211, 213 of slow release relay 21 open, and again transmitting one impulse to add coil 28 to move contact arm 56 to the next contact 53.

Such action would continue as long as contacts 181, 185 remain closed, but upon the next energization of coil 126 of the 10¢ relay, the wheel 187 is moved so that the extension 189 on switch arm 183 drops into a notch 188 and contacts 181, 185 are opened. It is, therefore, impossible to energize the add coil 28 or to re-energize the 10¢ relay coil 126 until another dime is used, and operation of the 10¢ relay and add coil ceases and contacts 211, 213 of the slow release relay 21 close. It is apparent, therefore, that when a dime is utilized, the 10¢ relay coil 126 is energized three times and the add coil 28 is energized twice to establish two units or credits.

Assuming now that a quarter is initially inserted in the apparatus, a circuit is established from line L1, through conductors 270, 271, a conductor 286, contacts 265, 266, a conductor 287, through the 25¢ relay coil 127, and a conductor 288 back to line L2 through conductor 273. The relay coil 127 is thus energized and wheel moved a sufficient distance to close contacts 182 and 186. The 25¢ relay now functions in an identical manner as described with respect to the 10¢ relay but the coil 127 thereof is energized six times before contacts 182, 186 are opened to terminate such operation and add coil 28 is energized five times, thus moving

contact arm 56 in five steps to the fifth contact 53d from initial contact 53c.

When coil 127 is energized and contacts 182, 186 closed, normally open contacts 156, 162 are closed and normally open contacts 157, 163 are opened. Closing of contacts 156, 162 establishes the following circuits. From line L1 through conductors 270, 282, a conductor 289, contacts 182, 186, a conductor 291 to terminal 201 of movable contact arm 153 through contacts 156, 162, a conductor 292 to terminal 194 of fixed switch arm 142 of the 10¢ relay 18, through conductor 285, slow release relay coil 205 and to line L2 through conductor 273, thus energizing the slow release relay coil 205 and opening contacts 211, 213. Another circuit is established which follows the one just described from line L1 to the conductor 285, whereupon it branches and includes conductor 284, add coil 28, and conductors 275, 277 to line L2. Thus the add coil 28 is energized each time contacts 153, 162 are closed.

Opening of contacts 157, 163, however, de-energizes the coil 127 and contacts 156, 162 are thereby opened and contacts 157, 163 are closed. A circuit is then established from line L1, through conductors 270, 282 and 289, through contacts 182, 186, through conductor 291, coil 127, and conductors 288, 273 back to line L2. Coil 127 is, therefore, reenergized and contacts 157, 163 opened and contacts 156, 162 closed, again establishing circuits to the slow release relay coil 205 and to add coil 28. Contact arm 56 is thus advanced one step and slow release relay 21 maintains contacts 211, 213 open. Obviously, coil 127 is again deenergized.

Upon the sixth energization of coil 127, the wheel 191 is moved to a position wherein extension 193 of contact arm 184 enters a notch 192 in wheel 191 and contacts 182, 186 are opened, thus preventing further energization of coils 127, 205 and 28 until an additional coin is deposited. The slow release contacts 211, 213 thereupon close.

All the circuits thus far described are D. C. circuits.

As stated before, the example of the apparatus shown is wired to dispense an article priced between 30¢ and 35¢ and at least 35¢ must be placed in the coin chute to effect delivery of an article.

First, it is assumed that exactly 35¢ has been deposited in nickels, dimes or quarters. By the mechanism and circuits thus far described, the contact arm 56 is moved to the seventh contact 53b from initial contact 53c. The slow release relay 21 at this time permits contacts 211, 213 to close and the following circuits are established, some being A. C. circuits from A. C. taps A1 and A2 on the rectifier 27.

One A. C. circuit is immediately established as soon as contact arm 56 reaches contact 53d from A1 to line 301 to slide contact 54, thence to the rotatable contact arm 56, through a conductor 302, lower coil 84 of interlock relay 17 and to tap A2 through a conductor 303. Coil 84 is thereby energized and closes all contacts associated with the switch, including contacts 103, 109. The latch 92 maintains the switches closed.

A D. C. circuit is also established from line L1 through conductor 270, a conductor 293, contacts 211, 213, a conductor 294 to terminal 116, contacts 103, 109 of relay 17, terminal 113, a conductor 295, a conductor 296, normally closed

contacts 237, 239 of interlock switch 23, through conductor 297, through normally closed contacts 47, 50b of subtract switch 45, through a conductor 298, subtract coil 39 and a conductor 299 to line L2. Thus, the rotatable contact arm is rotated counterclockwise toward the initial contact 53c from contact 53b. The circuit to the coil 84 of interlock relay 17, is, therefore, broken but latch 92 maintains the switches closed.

Since subtract coil 39 has already been energized and rotatable contact arm 56 moved from contacts 53c, closing of the intermediate relay contacts 226, 228 coincides with movement of the rotatable switch arm 56 to contact 53a. A circuit is, therefore, established from A. C. line 301 through the rotatable contact 56, contact 53a, a conductor 307 to terminal 112 of interlock relay 16, through closed contacts 102, 108 through terminal 115, through a conductor 308 to lower coil 58 of interlock relay 16, through a conductor 309 which connects with A. C. line 303. The coil 58 is thereby energized and contacts 72, 76 are opened, while contacts 71, 75 are closed. Opening of the contacts 72, 76 prevents energization of the coil 221 of the intermediate relay and open contacts 226, 228 thereof.

A circuit is also established from A. C. line 301 through contact 56, contact 53a, conductor 307, closed contacts 102, 108 of interlock relay 17, through terminal 115, through a conductor 309 to the article delivery or vending solenoid coil 246, and through a conductor 311 to A. C. terminal A2. The vending solenoid coil 24 is therefore energized and one package is delivered. Likewise, if pennies in change are to be delivered, the penny magazine is filled. The penny solenoid 26 is energized each time the vending solenoid 24 is energized through a conductor 314 connecting with conductor 309, and a conductor 315 connecting with conductor 311.

When the subtract coil 39 is de-energized, the contacts 47, 50b again close and a circuit is established from line L1 through conductors 270, 293, closed contacts 211, 213 of the slow release relay 21, conductor 294, closed contacts 103, 109 of interlock relay 17, conductors 295, 296, closed contacts 237, 239 of interlock switch 23, conductor 297 through closed contacts 47, 50b, through conductor 298, subtract coil 39, and conductor 299, back to line L2. The rotatable contact arm 56 is therefore stepped back an additional contact 23, but no further circuits are established until it reaches the initial contact 53c. Both the interlock relays 16 and 17 are latched in their lowered position by latches 64 and 92, respectively. As soon as the contacts 47, 50b close to energize the subtract coil 39, they are again opened to de-energize the subtract coil and this procedure continues so long as contacts 103, 106 remain closed.

When the movable contact arm 56 reaches the initial contact 53c, an A. C. circuit is established from the A. C. line 301, through the contact arm 56, contact 53c, conductors 278 and 316 to terminal 117 of interlock relay 17, through conductors 316a, 107, closed contacts 71, 75 of interlock relay 16, conductor 317 through upper coil 59 of interlock relay 16, and back to A. C. line 303. Coil 59 of interlock relay 16 is thereby energized. At the same time an A. C. circuit is established from conductor 316, terminal 117, contacts 101, 107, terminal 114, conductor 323, coil 85, conductor 322, back to A. C. line 303. The upper coil 85 of interlock relay 17 is thereby energized simultaneously with the coil 59 of

interlock relay 16, the latches 64 and 92 are tripped and all contacts are opened in both relays, except contacts 72, 76 of interlock relay 16, which are closed. The complete circuit is then conditioned for another vending operation and power is removed from the subtract coil 39 because of the opening of contacts 103, 106. Assuming now that more than 35¢ in various coins is deposited, it is first to be noted that devices of this type are generally equipped with an excess coin ejecting mechanism in the coin chute. Such mechanisms operate to return coins in excess of the amount for which change should be made. In other words, with the apparatus set to vend an article priced between 30¢ and 35¢, if more than two quarters are dropped in the coin chute, the additional quarters will be automatically returned. Likewise, if a quarter and a nickel, for example, are first dropped in the coin chute and then more than one dime is dropped, the additional dimes will be returned. Such excess coin mechanisms are standard equipment sold with coin chutes and are usually operated magnetically. Control of these magnetic devices is accomplished with contacts (not shown) on interlock relay 17 normally closed. Because of the fact that such mechanisms are standard commercial products and form no part of the present invention, further description is dispensed with.

Assuming now, for example, that two quarters are inserted in the coin chute, the quarter contacts 265, 266 will be closed twice in rapid succession, but the quarter impulse relay 19 operates rapidly to transmit ten (10) impulses to the add coil 28, which in turn moves the contact arm 56 to the tenth contact 53 in a clockwise direction, starting from the initial contact 23c. The contact arm 56 passes the contacts 53a and 53c, but no circuits are set up to the other parts of the apparatus because of the fact that the contacts 211, 213 of the slow release relay 21 are open as long as the quarter impulse relay 19 is operating, except that coil 84 of interlock relay 17 is energized when arm 56 passes contact 53b through the circuit described above.

As soon as the impulse relay 19 stops operation and the slow release relay 21 is deenergized so that contacts 211, 213 close, a D. C. circuit is established, as described before, from line L1 through conductors 270, 293, closed contacts 211, 213 of the slow release relay 21, normally closed contacts 103, 106 of the interlock relay 17, through conductors 295, 296, closed contacts 237, 239 of the interlock switch 23, conductor 297, closed contacts 47, 50b, conductor 298 through subtract coil 39 and back to line L2 through conductor 299. The subtract coil therefore steps the switch arm 56 back one contact and as soon as the subtract coil is energized the contacts 47, 50b open and contacts 46, 48 close.

A circuit is then set up to the intermediate relay 22 through conductor 304, normally closed contacts 72, 76 of interlock relay 16, through conductor 305 to the coil 221 of intermediate relay 22 and through conductor 306 back to line L2. The intermediate relay is therefore operated and contacts 226, 228 thereof are closed. A circuit is therefore established from A. C. terminal A-2 through conductor 311, closed contacts 226, 228 of intermediate relay 22, conductor 312, through the change pay-out solenoid, in this case being a nickel pay-out solenoid 25 and through conductor 313 to A. C. terminal A-1. The nickel pay-

out solenoid 25 is therefore energized to drop one nickel in change.

As soon as the subtract relay contacts 47, 50b are opened and contacts 46, 48 are closed, the subtract coil 39 is deenergized and contacts 47, 50b again close. The subtract coil is therefore again energized, the contact arm 56 is stepped back one contact 53 and the intermediate relay coil 221 is again energized to close contacts 226, 228 and re-energize the nickel pay-out solenoid 25 so that a second nickel is paid out in change.

The same process is again repeated and a third nickel is paid out in change at the time the contact arm 56 reaches the contact 53b. The same sequence of operations now occurs as explained hereinbefore, when the exact amount of money, that is, 35¢ for obtaining the article to be vended, is placed in the machine. The interlock relays 16 and 17 are energized by the time the contact arm 56 reaches the contact 53a, and the vending solenoid 24 is energized to deliver the article to be vended.

It will be obvious that each time the vending solenoid 24 operates, the slide 249 is withdrawn to permit the article to be vended to be delivered.

Likewise, each time pennies in change are to be delivered, the slide 253 permits any desired number of pennies to be delivered with the vended article. Similarly, the slide 254 operates one each time a nickel in change is to be made.

In order to insure sufficiently slow operation of the nickel change solenoid 25, so that the correct change will be delivered and so that it will not operate at the high speed which the subtract relay and intermediate relay are capable of, the interlock switch 23 is provided. Each time the coil of the nickel solenoid 25 operates, it opens contacts 237, 239 of the interlock switch and does not effect closure of these contacts again until the armature has made its full stroke and returned to its initial position. Obviously, this prevents reenergization of the subtract coil 39 and the intermediate relay coil 221 until contacts 237, 239 are again closed, thus preventing too rapid pulsations of the nickel change pay-out solenoid 25.

The same sequence of operations occurs as described above if, for example, 40¢ in coins is placed in the coin chutes. This may comprise nickels, dimes and quarters and each time a nickel is dropped in the coin chute, the nickel contacts close and give one credit. Each time a dime is dropped in the coin chute, the dime impulse relay 18 operates to give two credits. Each time a quarter is dropped in the coin chute, the quarter impulse relay 19 operates to give five credits.

Obviously, the apparatus may be set up to vend articles of almost any given price. If nickels, dimes and quarters are to be used, relocating the contacts 53a and 53b will permit various priced items to be vended up to the capacity of the apparatus to contain contacts 53. If higher priced articles are to be vended, the nickel coin chute might be changed, for example, to a dime coin chute; the dime relay to a quarter relay; and the quarter relay to a half dollar relay. The remainder of the apparatus, except for the coin change chute, which might then be set up to give change in dimes, or dimes and nickels, would remain the same and the operation of the apparatus would be in accordance with the above description.

It is also believed to be obvious that other well known types of devices responsive to various de-

nominations of coins and other types of add and subtract stepper mechanisms may be substituted for the specific devices shown and described herein. Furthermore, other well known types of interlock devices may be substituted for the interlock relays described herein. Such substitutions would not depart from the spirit and intent of the invention and the invention is not intended to be limited to the specific devices shown, except as set forth in the appended claims.

From the foregoing, it will be apparent that I have provided an extremely simple mechanism which will operate very rapidly to dispense articles of different values and give the correct change. It will also be apparent that I have provided a novel sequence of operations and electrical circuit for carrying out the same.

Some changes may be made in the construction and arrangement of the parts of my coin controlled apparatus and change maker without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. Apparatus for vending an article comprising an electrical circuit connected to opposite sides of a source of power, a plurality of normally open coin responsive switch means in said circuit adapted to be closed by coins of different denominations, one of said coin responsive switch means being responsive to a coin representing a single unit and another being responsive to a coin representing a multiple of a single unit, an electrically operated add stepper means and an electrically operated subtract stepper means for respectively crediting and debiting units represented by said coins, said add stepper means being energized from said circuit by closure of said single unit coin switch, a set of spaced contacts, at least some of which are connected to one side of said circuit, contact means movable by said stepper means from an initial one of said spaced contacts to subsequent contacts and then back to the initial contact, said movable contact means being connected to the other side of said circuit, an impulse means responsive to said other coin responsive switch means, means for translating the impulses from said impulse means to operate said add stepper means to credit the proper number of units and to move said contact means past a plurality of said subsequent contacts, article delivery means, an electrical relay including a pair of coils, means for energizing one of the coils of said relay when said add stepper means has moved said movable contact means a sufficient distance to pass a first predetermined contact and to engage or pass a second predetermined contact, the energization of said coil serving to prepare a plurality of circuits, one of which includes the first predetermined contact, means for energizing said subtract stepper means to return said contact means to said initial contact after the add stepper means has credited units corresponding to all of the coins utilized, an electrically operated means including said one of the plurality of prepared circuits for operating said article delivery means when said movable contact passes or engages said first predetermined contact after said one circuit has been prepared.

2. Apparatus for vending an article comprising an electrical circuit connected to opposite

sides of a source of power, a plurality of normally open coin responsive switch means in said circuit adapted to be closed by coins of different denominations, one of said coin responsive switch means being responsive to a coin representing a single unit and another being responsive to a coin representing a multiple of a single unit, an electrically operated add stepper means and an electrically operated subtract stepper means for respectively crediting and debiting units represented by said coins, said add stepper means being directly energized from said circuit by closure of said single unit coin switch, a set of spaced contacts, at least one of which is always connected by one individual circuit of a plurality of possible individual circuits to one side of said first mentioned circuit, contact means movable by said stepper means from an initial one of said spaced contacts to subsequent contacts and then back to the initial contact, said movable contact means being connected to the other side of said first mentioned circuit, an impulse means responsive to said other coin responsive switch means, means for translating the impulses from said impulse means to operate said add stepper means to credit the proper number of units and to move said contact means past a plurality of said subsequent contacts, article delivery means, an electrical relay including a pair of coils, means for energizing one of the coils of said relay when said add stepper means has moved said movable contact means a sufficient distance to pass a first predetermined contact and to engage or pass a second predetermined contact, the energization of said coil serving to prepare a plurality of said individual circuits, one of which includes said first predetermined contact, means for energizing said subtract stepper means to return said contact means to said initial contact after the add stepper means has credited units corresponding to all of the coins utilized, electrically operated means including said prepared circuit which includes said first predetermined contact for operating said article delivery means when said movable contact passes or engages said first predetermined contact after said one circuit has been prepared, an electrically operated change return operatively associated with said subtract stepper means for delivering the correct change in coins corresponding to a denomination representing a single unit.

3. Apparatus for vending an article comprising an electrical circuit connected to opposite sides of a source of power, a plurality of normally open coin responsive switch means in said circuit adapted to be closed by coins of different denominations, one of said coin responsive switch means being responsive to a coin representing a single unit and another being responsive to a coin representing a multiple of a single unit, an electrically operated add stepper means and an electrically operated subtract stepper means for respectively crediting and debiting units represented by said coins, said add stepper means being energized from said circuit by closure of said single unit coin switch, a set of spaced contacts, at least some of which are connected to one side of said circuit, contact means movable by said stepper means from an initial one of said spaced contacts to subsequent contacts and then back to the initial contact, said movable contact means being connected to the other side of said circuit, an impulse means responsive to said other coin responsive switch means, means for translating the impulses from said impulse means to operate said

add stepper means to credit the proper number of units, article delivery means, electrically operated means for preparing an electrical circuit for operating the article delivery means when said add stepper means has moved said movable contact means a sufficient distance to pass a first predetermined contact and engage or pass a second predetermined contact, to thereby connect said electrically operated means to said circuit, means for thereupon energizing said subtract stepper means to return said contact means to said initial contact after the add stepper means has credited units corresponding to all of the coins utilized, said movable contact means energizing said prepared electrical circuit for operating said article delivery means when said contact means is moved by said subtract stepper means into engagement with or past said first predetermined contact, and electrically operated means for delivering the correct change in coins corresponding to a denomination representing a single unit when said add stepper means have moved said contact means past said second predetermined contact and said subtract stepper means returns said contact means in successive engagement with one or more contacts up to and including said second predetermined contact, and electrical means for insuring that said article delivery means and said change delivery means are conditioned to again deliver an article and change when said contact means returns to said initial contact.

4. Apparatus for vending an article comprising an electrical circuit, a plurality of normally open coin responsive switch means in said circuit adapted to be closed by coins of different denominations, one of said coin responsive switch means being responsive to a coin representing a single unit and another of said coin responsive switch means being responsive to a coin representing a multiple of said single unit, add means and subtract means for crediting and debiting units represented by said coin, said add means being energized by closure of said single unit coin switch, an impulse means responsive to said other coin responsive switch means, means for translating the impulses from said impulses means to operate said add means to credit the proper number of units, electrically operated article delivery means, means for energizing said subtract means to debit a total number of units equaling the total number of units credited after all the units have been credited, a contact member movable in one direction by said add means and in an opposite direction by said subtract means, means including said contact member for preparing an article delivery circuit after a predetermined number of units have been credited, means including said contact member for energizing said prepared article delivery circuit so as to operate said article delivery means after a second predetermined number of units have been debited, change pay-out means, and means controlled by the subtract means for operating said change pay-out means when coins have been inserted totalling more than the price of the article to be vended.

5. Apparatus for vending an article comprising an electrical circuit, a plurality of normally open coin responsive switch means in said circuit adapted to be closed by coins of different denominations, one of said coin responsive switch means being responsive to a coin representing a single unit and another of said coin responsive switch means being responsive to a coin

representing a multiple of said single unit, and add and subtract means for crediting and debiting units represented by said coin, said add means being energized by closure of said single unit coin switch, an impulse means responsive to said other coin responsive switch means, means for translating the impulses from said impulse means to operate said add means to credit the proper number of units, electrically operated article delivery means, means for energizing said subtract means to debit a total number of units equaling the total number of units credited, a movable contact member adapted to be moved in one direction by said add means and in an opposite direction by said subtract means, means including said movable contact member for preparing an article delivery circuit after a predetermined number of units have been credited, means including said movable contact member for energizing said prepared article delivery circuit so as to operate said article delivery means after a second predetermined number of units have been debited, change pay-out means, means controlled by the subtract means for operating said change pay-out means when coins have been inserted totalling more than the price of the article to be vended, and means energized by closure of any coin switch for preventing debiting of units during the time units are being credited.

6. Apparatus for vending an article comprising an electrical circuit, a plurality of normally open coin responsive switch means in said circuit adapted to be closed by coins of different denominations, one of said coin responsive switch means being responsive to a coin representing a single unit and another of said coin responsive switch means being responsive to a coin representing a multiple of said single unit, add and subtract means for crediting and debiting units represented by said coin, said add means being energized by closure of said single unit coin switch, an impulse means responsive to said other coin responsive switch means, means for translating the impulses from said impulse means to operate said add means to credit the proper number of units, electrically operated article delivery means, means for energizing said subtract means to debit a total number of units equaling the total number of units credited, a movable contact member adapted to be moved in one direction by said add means and in an opposite direction by said subtract means, means including said movable contact member for preparing an article delivery circuit after a predetermined number of units have been credited, means including said movable contact member for energizing said prepared article delivery circuit so as to operate said article delivery means after a second predetermined number of units have been debited, change pay-out means, means controlled by the subtract means for operating said change pay-out means when coins have been inserted totalling more than the price of the article to be vended, and means for preventing debiting of units during the time units are being credited, said last means comprising a slow release relay interposed in the circuit between the coin switches and the add means.

7. Apparatus for vending an article comprising an electrical circuit, a plurality of normally open coin responsive switch means in said circuit adapted to be closed by coins of different denominations, one of said coin responsive switch means being responsive to a coin representing a single unit and another of said coin responsive

switch means being responsive to a coin representing a multiple of said single unit, add means and subtract means for crediting and debiting units represented by said coin, said add means being energized by closure of said single unit coin switch, an impulse means responsive to said other coin responsive switch means, means for translating the impulses from said impulse means to operate said add means to credit the proper number of units, electrically operated article delivery means, means for energizing said subtract means to debit a total number of units equaling the total number of units credited, a movable contact member adapted to be moved in one direction by said add means and in an opposite direction by said subtract means, means including said movable contact member for preparing an article delivery circuit after a predetermined number of units have been credited, means including said movable contact member for energizing said prepared article delivery circuit so as to operate said article delivery means after a second predetermined number of units have been debited, change pay-out means, means controlled by the subtract means for operating said change pay-out means when coins have been inserted totalling more than the price of the article to be vended, and means for insuring the delivery of each coin in change before said add and subtract means condition the apparatus to deliver a subsequent coin in change, said last means comprising an interlock switch operated by the change pay-out means interposed in the circuit to the subtract means.

8. Apparatus for vending an article comprising an electrical circuit, a plurality of normally open coin responsive switch means in said circuit adapted to be closed by coins of different denominations, one of said coin responsive switch means being responsive to a coin representing a single unit and another of said coin responsive switch means being responsive to a coin representing a multiple of said single unit, add means and subtract means for crediting and debiting units represented by said coin, said add means being energized by closure of said single unit coin switch, an impulse means responsive to said other coin responsive switch means, means for translating the impulses from said impulse means to operate said add means to credit the proper number of units, electrically operated article delivery means, means for energizing said subtract means to debit a total number of units equaling the total number of units credited, a movable contact member adapted to be moved in one direction by said add means and in an opposite direction by said subtract means, means including said movable contact member for preparing an article delivery circuit after a predetermined number of units have been credited, means including said movable contact member for energizing said prepared article delivery circuit so as to operate said article delivery means after a second predetermined number of units have been debited, change pay-out means, means controlled by the subtract means for operating said change pay-out means when coins have been inserted totalling more than the price of the article to be vended, and means for reducing the speed of operation of the change pay-out means, said last means comprising an intermediate relay disposed in the circuit to the change pay-out means.

9. Apparatus for vending an article comprising an electrical circuit, a plurality of normally

open coin responsive switch means in said circuit adapted to be closed by coins of different denominations, one of said coin responsive switch means being responsive to a coin representing a single unit and another of said coin responsive switch means being responsive to a coin representing a multiple of said single unit, add means and subtract means for crediting and debiting units represented by said coin, said add means being energized by closure of said single unit coin switch, an impulse means responsive to said other coin responsive switch means, means for translating the impulses from said impulse means to operate said add means to credit the proper number of units, electrically operated article delivery means, means for energizing said subtract means to debit a total number of units equaling the total number of units credited, a movable contact member adapted to be moved in one direction by said add means and in an opposite direction by said subtract means, means including said movable contact member for preparing an article delivery circuit after a predetermined number of units have been credited, means including said movable contact member for energizing said prepared article delivery circuit so as to operate said article delivery means after a second predetermined number of units have been debited, change pay-out means, means controlled by the subtract means for operating said change pay-out means when coins have been inserted totalling more than the price of the article to be vended, said means for operating the electric delivery means including an interlock relay, said interlock relay having latching means adapted to latch said interlock relay in one position during the time that the add means is crediting units and having means for releasing said latching means at the end of each vending cycle.

10. Apparatus for vending an article comprising an electrical circuit connected to opposite sides of a source of power, a plurality of normally open coin responsive switch means in said circuit adapted to be closed by coins of different denominations, one of said coin responsive switch means being responsive to a coin representing a single unit and another being responsive to a coin representing a multiple of a single unit, an electrically operated add stepper means and an electrically operated subtract stepper means for respectively crediting and debiting units represented by said coins, said add stepper means being energized from said circuit by closure of said single unit coin switch, a set of spaced contacts, at least one of which is always connected by one individual circuit of a plurality of possible individual circuits to one side of said first mentioned circuit, contact means movable by said stepper means from an initial one of said spaced contacts to subsequent contacts and then back to the initial contact, said movable contact means being connected to the other side of said first mentioned circuit, an impulse means responsive to said other coin responsive switch means, means for translating the impulses from said impulse means to operate said add stepper means to credit the proper number of units and to move said contact means past a plurality of said subsequent contacts, article delivery means, an electrical relay including a pair of coils, means for energizing one of the coils of said relay when said add stepper means has moved said movable contact means a sufficient distance to pass a first predetermined contact and to engage or pass a sec-

ond predetermined contact, the energization of said coil serving to prepare a plurality of said individual circuits, one of which includes said first predetermined contact, means for energizing said subtract stepper means to return said contact means to said initial contact after the add stepper means has credited units corresponding to all of the coins utilized, electrically operated means including said prepared circuit which includes said first predetermined contact for operating said article delivery means when said movable contact passes or engages said first predetermined contact after said one circuit has been prepared, a slow release coil energized by closure of any coin switch for preventing operation of said article delivery means while credits are being added, and latch means movable into operative position simultaneously with the preparation of said individual circuits to maintain said plurality of said individual circuits in prepared condition until the cycle of operation is completed.

11. Apparatus for vending an article comprising an electrical circuit connected to opposite sides of a source of power, a plurality of normally open coin responsive switch means in said circuit adapted to be closed by coins of different denominations, one of said coin responsive switch means being responsive to a coin representing a single unit and another being responsive to a coin representing a multiple of a single unit, an electrically operated add stepper means and an electrically operated subtract stepper means for respectively crediting and debiting units represented by said coins, said add stepper means being directly energized from said circuit by closure of said single unit coin switch, a set of spaced contacts, at least one of which is always connected by one individual circuit of a plurality of possible individual circuits to one side of said first mentioned circuit, contact means movable by said stepper means from an initial one of said spaced contacts to subsequent contacts and then back to the initial contact, said movable contact means being connected to the other side of said first mentioned circuit, an impulse means responsive to said other coin responsive switch means, means for translating the impulses from said impulse means to operate said add stepper means to credit the proper number of units and to move said contact means past a plurality of said subsequent contacts, article delivery means, an electrical relay including a pair of coils, means for energizing one of the coils of said relay when said add stepper means has moved said movable contact means a sufficient distance to pass a first predetermined contact and to engage or pass a second predetermined contact, the energization of said coil serving to prepare a plurality of said individual circuits, one of which includes said first predetermined contact, means for energizing said subtract stepper means to return said contact means to said initial contact after the add stepper means has credited units corresponding to all of the coins utilized, electrically operated means including said prepared circuit which includes said first predetermined contact for operating said article delivery means when said movable contact passes or engages said first predetermined contact after said one circuit has been prepared, a slow release coil energized by closure of any coin switch for preventing operation of said article delivery means while credits are being added, latch means movable into operative position simultaneously with the preparation of said

individual circuits to maintain said plurality of said individual circuits in prepared condition until the cycle of operation is completed, and electrical means including energization of one of said prepared circuits for releasing said latch means when the cycle of operation is completed.

12. Crediting apparatus comprising an electric circuit, a plurality of normally open switches in said circuit adapted to be independently moved to closed position and reopened, and add and subtract means for crediting and debiting units, the number of credits depending upon which of said switches is closed or how many times one or more of said switches is closed, one of said switches being adapted to energize the add means to credit one unit and another of said switches adapted to energize the add means to credit more than one unit, a set of spaced contacts, at least one of which is always connected by one individual circuit of a plurality of possible individual circuits to one side of said first mentioned circuit, contact means movable by said add and subtract means from an initial contact to subsequent contacts and then back to the initial contact, said movable contact being connected to the other side of said first mentioned circuit, said add means being energized to add one credit when the switch for one unit is closed, an impulse means which is energized a predetermined number of times and then deenergized when said other switch is closed, means for translating the impulses from said impulse means to said add means to credit the proper number of units and to move said contact means past a plurality of said subsequent contacts, an electrically operated device, means for preparing a plurality of circuits, one of which is an energizing circuit for said electrically operated device, when said contact means has passed a first predetermined contact and engaged or passed a second predetermined contact, means for energizing said subtract means to move said contact means back to its initial position after all units have been credited, and means for energizing said prepared energizing circuit so as to operate said electrically operated device upon said contact means engaging said first predetermined contact after said circuit has been prepared.

13. Crediting apparatus comprising an electric circuit, a plurality of normally open switches in said circuit adapted to be independently moved to closed position and reopened, add means and subtract means for crediting and debiting units, the number of credits depending upon which of said switches is closed or how many times one or more of said switches is closed, one of said switches being adapted to energize the add means to credit one unit and another of said switches adapted to energize the add means to credit more than one unit, a set of spaced contacts at least one which is always connected by one individual circuit of a plurality of possible individual circuits to one side of said first mentioned circuit, contact means movable by said add and subtract means from an initial contact to subsequent contacts and then back to the initial contact, said movable contact being connected to the other side of said first mentioned circuit, said add means being energized to add one credit when the switch for one unit is closed, an impulse means which is energized a predetermined number of times and then deenergized when said other switch is closed, means for translating the impulses from said impulse means to said add means to credit the proper number of units and to move said contact means past a plurality of said subsequent contacts.

tacts, an electrically operated device, means for preparing a plurality of circuits, one of which is an energizing circuit for said electrically operated device, when said contact means has passed a first predetermined contact and engaged or passed a second predetermined contact, means for energizing said subtract means to move said contact means back to its initial position after all units have been credited, means for energizing said one prepared circuit so as to operate said 10 electrically operated device upon said contact means engaging said first predetermined contact after said circuit has been prepared, and means energized by closure of any of said switches for preventing debiting of units during the time 15 units are being credited.

MARVIN G. NELSEN.
